United States Patent Office.

JACOB HOERT, OF NEW YORK, N. Y.

Letters Patent No. 65,222, dated May 28, 1867.

IMPROVED BEDSTEAD.

The Schedule referred to in these Letters Patent and making part of the same.

TO ALL WHOM IT MAY CONCERN:

Be it known that I, JACOB HOERT, of the city, county, and State of New York, have invented a new and useful improvement in Folding-Bedsteads; and I do hereby declare the following to be a full, clear, and exact description thereof, which will enable those skilled in the art to make and use the same, reference being had to the accompanying drawing forming part of this specification, in which drawing—

Figure 1 represents a plan or top view of this invention.

Figure 2 is a longitudinal vertical section of the same, showing the bedstead unfolded in black outlines and folded in red outlines.

Similar letters indicate corresponding parts.

This invention relates to a bedstead in which a flexible bottom is secured by loops and lacing-cords, and the frame of which is composed of four middle legs which connect by parallel hinged bars with the outer legs, in combination with a head and foot-piece, in such a manner, that, by unfolding the bedstead, the outer legs are brought in a position parallel to the middle or main legs, being retained by the parallel bars, and when the frame or bedstead is folded, the outer legs, in combination with the lower set of parallel bars, form toggle-braces, whereby the frame is securely retained in its folded position.

A represents a piece of canvas, which is secured to the frame B of the bedstead by means of loops and lacing-cords, as clearly shown in fig. 1 of the drawing, so as to form a flexible bed-bottom. The frame B is composed of three sections, viz, two end sections, which are supported by hinged legs, D, and from the outer ends of which rise the head and foot-pieces, and the middle section, which is supported by the legs E, and to which the end sections are connected by pivots, a. The legs D and E are also connected by bars, H, which are connected to said legs by pivots, b c, and which, when the bedstead is unfolded, are parallel to the side slats of the end sections of the frame, as clearly shown in fig. 2 of the drawing. When the bedstead is folded, the end sections of the frame occupy the position shown in red outlines in fig. 2, and the bars H, together with the legs D, form the toggle-braces which prevent the spontaneous unfolding of the bedstead.

What I claim as new, and desire to secure by Letters Patent, is—

The arrangement and combination of the toggle-braces H D, legs E, and frame B with the flexible bottom A, constructed and operating substantially as and for the purpose described.

JACOB HOERT.
